UNITED STATES PATENT OFFICE.

JOHN WOODS, OF MELBOURNE, VICTORIA.

RAILWAY-BRAKE.

SPECIFICATION forming part of Letters Patent No. 273,214, dated February 27, 1883.

Application filed October 21, 1882. (No model.) Patented in Victoria December 7, 1881, No. 3,131.

To all whom it may concern:

Be it known that I, JOHN WOODS, a subject of the Queen of Great Britain, residing at Melbourne, in the British Colony of Victoria, 5 engineer, and a member of the Legislative Assembly of the said colony, have invented certain new and useful Improvements in Railway-Brakes, (for which I have obtained a patent in the said British Colony of Victoria, No. 10 3,131, bearing date the 7th day of December, 1881,) of which the following is a specification.

This invention consists of certain improvements in railway-brakes, which improvements are applicable to all kinds of railway rolling 15 stock, excepting locomotives, but have been specially designed for railway-trucks.

By my present invention I utilize the brakes now commonly in use on railway-trucks, in which, as is well known, the brake-blocks are 20 forced on the wheels by means of a weighted lever, and released therefrom by such lever being lifted and supported in a suitable catch. Now, I allow the brake-blocks and their weighted levers to remain as before; but I dispense 25 with the catches and substitute fluid-pressure for the hand-power in lifting off the brakes. Thus I convey fluid, and preferably hydraulic pressure, to a plunger or piston, which is connected to said weighted levers, so that when necessary they may be lifted and when necessary allowed to fall. This fluid-pressure I 30 convey to the brake-levers on each truck from a main line of piping coupled together between each truck, and when such pressure is hydraulic, receiving it through an accumulator on the engine in precisely the same way as is described and represented in the specification and drawings of my invention, entitled "improvements in railway-brakes," for which 35 I have already obtained United States Letters Patent No. 227,400, and dated the 11th day of May, 1880.

I will now describe my invention with reference to the accompanying drawings, which 45 illustrate my method of applying hydraulic pressure for working the brakes, because I believe that pressure to be the best, although any other fluid-pressure—such as air—may be used, if preferred. In these drawings I show 50 the base-frame or sole-plate of a railway-truck with the wheels and brakes attached thereto.

Figure 1 represents the bed frame-work of a car, its wheels, &c., provided with my improvement; and Fig. 2 is a side elevation of the same. Fig. 3 is an end elevation, partly in 55 section; and Fig. 4 is a perspective view of the cylinder, its piston, and a portion of the weighted lever, the forward end of said lever being broken away. In this view one end of the branch pipe is shown in connection with 60 the cylinder.

A A are the brake-blocks, and A' their weighted lever, E being the weight.

B is a pressure-cylinder, and C its plunger or piston.

D is a main pressure-pipe, secured to the under side of the car and running the length thereof. Any suitable means may be employed for connecting the end of the pipe to the pipes on an adjoining car, or to the pipe 70 on the locomotive, communicating with the accumulator previously referred to.

D' is a branch pipe, connecting the pipe D to the cylinder B.

B' are hangers supporting the cylinder, and 75 B² and B³ are stays thereto.

A² represents an arm pivoted at A¹⁰ to the lever A'.

A³ is a brake-rod provided with a perforated end, A⁴, whereby the arm A² may be adjusted 80 therewith so as to conform with the wear on the brake-blocks.

A⁵ is the pivoted end of rod A³ where it engages one of the block-plates A⁶. Said block-plates are secured to the blocks A, and are pivoted at their upper ends to the frame, and by means of which the block is hung and supported.

A⁹ is a rod pivoted at each end to the brake-blocks.

Plunger C has a groove or slot, C', in which to hold the weighted lever. The lever A' is shown by dotted lines at A² in its lowest possible position—namely, with the brake on the wheels when the blocks are nearly worn out.

When the brakes are required to be taken off, I force pressure (as described in the specification of my previously-patented invention hereinbefore referred to) through pipe D into pipe D' and cylinder B. This pressure raises 90 plunger C, whose groove C' lifts weighted lever A', and thus takes the brake-blocks A off

the wheels. When the brakes are required to be put on, I simply release the pressure in the pipe D, when the weight on lever A' forces the blocks A onto the wheels in the ordinary way.

Should a locomotive and train of cars equipped with my improvement, as specified, become disengaged by accident, the pressure would be released from pipes D D' and cylinder B, which action would permit the weight E to descend, thereby forcing down the lever A', and causing the blocks A to be thrown in contact with the wheels, thereby automatically applying the brakes.

I am aware that it is not new to force brake-blocks against car-wheels by means of a weighted lever. I therefore do not claim such mechanism, broadly; but

What I do claim, and desire to secure by Letters Patent, is—

1. The brake-blocks A, both arranged in the

same manner or side with respect to the wheels, the hanger-plates A⁶, rod A³, pivoted to one of the hangers A⁶, and provided with an adjustable end with respect to arm A², the lever A', provided with weight E, in combination with the cylinder B and piston C, substantially as described, and for the purposes set forth.

2. The blocks A, hanger-plates A⁶, rod A³, adjustable rod A², lever A', provided with weight E and arm A², cylinder-hanger B', cylinder B, and piston C, all united as specified, in combination with the supply-pipes D and branch pipes D', adapted to receive and communicate power to the cylinder, whereby the piston and lever are operated in the manner and for the purposes set forth.

JOHN WOODS
